GLOW CATHODE FOR CATHODE RAY TUBES

Paul Görlich and Martin Ploke, Dresden, Germany, assignors to Zeiss Ikon Aktiengesellschaft, Dresden, Germany

Application January 17, 1938, Serial No. 185,455
In Germany December 22, 1936

4 Claims. (Cl. 250—27)

The invention relates to improvements in glow cathodes for cathode ray tubes, in particular Braun tubes, and is directed especially to glow cathodes provided with a high emission substance.

Cathodes of the type referred to have the disadvantage that the emission substance evaporates gradually during the operation of the cathode ray tube with the result that the emission capacity of the cathode decreases.

It is the principal object of the invention to provide a high emission cathode in which the evaporation of the emission substance is prevented as much as possible. This is accomplished by arranging the high emission substance in the interior of a heated cavity and arranging in front of the cavity one or more electrodes positively biased with respect to the potential applied to the recess. The purpose of the electrodes is to drive back to the cathode any vaporised particles which leave the cathode in the form of positively charged ions. This action may be amplified by arranging additional positive electrodes in front of the glow cathode.

It is also an object of the invention to provide means for heating the electrodes for retaining in this manner also the neutral particles in the interior of the cavity or for regenerating the cathode.

Still another object of the invention is to cover also the heatable electrodes in front of the cathode with an emission substance for producing in this manner a very capacious glow cathode.

The emission substance employed comprises preferably a compound of alkali metals, for instance a caesium compound, which is embedded in a weakly reducing or oxidising substance, as for instance the earth alkali-oxides. As examples of a caesium compound may be mentioned caesium sulphate or caesium azide which is applied in the form of an alcoholic paste which is permitted to dry in the air. When embedding the caesium compound in a reducing or oxidising substance, the latter is converted into a paste, for instance by dissolving it in alcohol, whereupon this paste is mixed with the caesium paste.

It is also possible to apply the alkali metals to the inner wall of the cavity and then apply on top of the same the oxide of the earth alkali metal. The presence of the oxide of the earth alkali metal causes the production of alkali oxide which evaporates to a smaller degree than the metal.

It may also be more suitable to apply the emission substance only to the bottom of the cavity and to apply to the side wall of the cavity a lining of a metal oxide which due to its higher

emission power absorbs any alkali atoms striking the same. If aluminum oxide is employed for this purpose, this material may at the same time be used as a heater element in which the electric heating wires are embedded.

In certain cases it may be advisable to provide the electrodes in front of the cathode with a coating of a metal oxide for absorbing the vaporised alkali metal.

The accompanying drawing illustrates diagrammatically and by way of example a few embodiments of the present invention:

Fig. 1 shows an electron gun comprising a high emission glow cathode in longitudinal section and a series of electrodes in front of the same, and

Fig. 2 shows a longitudinal section of a different construction of a glow cathode.

Referring to Fig. 1, the body 1 of the high emission cathode is provided at one end with a cylindrical cavity 2 whose bottom and side wall 20 is lined with a layer of emission substance 3. The other end of the body 1 has embedded therein a resistance wire 4 forming the heating element of the cathode and supplied with electric current by the source 5.

In front of the cathode and in axial alignment with the cavity 2 of the same is arranged in spaced relation from one another a series of screen electrodes 6, 7, 8 and 9 and a centrally apertured disc electrode 10. The electrodes 6, 7, 8, 9 and 10 are connected with positive voltage taps of a potentiometer 11 connected across the terminals of a source 12 and thus are positively biased with respect to the cathode.

In the embodiment of the invention illustrated in Fig. 2, the body 1a of the glow cathode is provided with a tubular cavity 2a. The electrodes 14, 15 and 16 arranged in this cavity constitute the high emission elements of the cathode. The electrode 14 consists of a circular disc provided at its circumference with a cylindrical flange, and the electrodes 15 and 16 consist each of a centrally apertured disc with a cylindrical flange at their outer circumference. The inner faces of the disc of the electrodes 14, 15 and 16 have applied thereto a layer 20 of emitting substance while the inner wall faces of the flanges of these electrodes are lined with a metal oxide 21.

In front of the outermost emitting electrode 16 and axially spaced therefrom is arranged an apertured disc anode 19 having at its outer circumference a cylindrical flange.

A potentiometer 11a connected across the terminals of a source of potential 12a is provided

with a plurality of taps connected with the electrodes 14, 15, 16 and 19.

Between each two electrodes is arranged an annular member 18 consisting of insulating material, as for instance a ceramic substance. The tubular body 1^a of the cathode is surrounded by a heating coil indicated at 22 and supplied with current from the source 5^a.

If desired the individual electrodes may be formed and used as electric lenses and/or may be treated to cause the emission of secondary electrons for increasing the efficiency of the electrodes.

What we claim is:

- 15 1. In a cathode ray device, an electron gun comprising a high emission glow cathode formed of a cathode body having at one end a cavity, an emission substance applied to the walls of said cavity, means for heating said cathode body, a 20 centrally apertured disc electrode axially spaced from said cathode body and at least one screen electrode mounted between said cathode and disc electrode in front of said cavity, and means positively biasing said screen electrode with respect to said cathode body so as to return any positive 25 ions which tend to leave said cavity.
2. In a cathode ray device, an electron gun comprising a high emission glow cathode formed of a cathode body having at one end a cavity, 30 an emission substance applied to the walls of said cavity, means for heating said cathode body, a centrally apertured anode in axial alinement with said cathode body, a plurality of axially alined and axially spaced screen electrodes mounted in 35 front of said cavity and between said cathode body and said anode, and means positively biasing each said screen electrodes with respect to potential applied to said cathode body and with re-

spect to the adjacent screen electrode which is closer to said cavity.

3. In a cathode ray device, an electron gun comprising a high emission glow cathode formed of a cathode body having at one end a cavity, an emission substance applied to the walls of said cavity, means for heating said cathode body, a centrally apertured anode, a plurality of axially alined and axially spaced screen electrodes mounted in front of said cavity and between said cathode body and said anode, said screen electrodes being provided with a coating of emission substance, and means positively biasing each of said screen electrodes with respect to potential applied to said cathode body, said last named means applying a successively higher potential to said screen electrodes in proportion to their distance from said cathode body. 5 10 15

4. In a cathode ray device, an electron gun comprising a high emission glow cathode formed of a cathode body having at one end a cavity, an emission substance applied to the walls of said cavity, means for heating said cathode body, a centrally apertured anode, a plurality of axially alined and axially spaced screen electrodes 20 25 mounted in front of said cavity and between said cathode body and said anode, said screen electrodes having oxidized surfaces for absorbing vaporized particles of said emission substance, and means positively biasing each said screen 30 electrodes with respect to the potential applied to said cathode body, said last named means applying a successively higher potential to said screen electrodes in proportion to their distance from said cathode body. 35
